UNITED STATES PATENT OFFICE.

CHARLES W. EDWARDS, OF ALLIANCE, OHIO.

WHIFFLETREE.

SPECIFICATION forming part of Letters Patent No. 426,176, dated April 22, 1890.

Application filed February 7, 1890. Serial No. 339,521. (No model.)

To all whom it may concern:

Be it known that I, CHARLES W. EDWARDS, a citizen of the United States, residing at Alliance, in the county of Stark and State of Ohio, have invented a new and useful Whiffletree, of which the following is a specification.

The invention relates to improvements in whiffletrees.

The object of the present invention is to provide a strong and durable whiffletree, in which the trace-hook or draft attachment will be cushioned to prevent any jar to the animals when starting a heavy load or during the passage of the vehicle over rough surfaces.

The invention consists in the construction and novel combination and arrangements of parts hereinafter fully described, illustrated in the accompanying drawings, and pointed out in the claims hereto appended.

In the drawings, Figure 1 is a perspective view of a whiffletree constructed in accordance with the invention. Fig. 2 is a horizontal sectional view. Fig. 3 is a vertical longitudinal sectional view. Fig. 4 is a reversed plan view. Fig. 5 is a detail view of one of the clip-plates.

Referring to the accompanying drawings, 1 designates a doubletree, which is constructed 30 of suitable material, preferably of wood, and provided with a rectangular opening 2, that is centrally arranged and adapted to receive a pin to secure the doubletree to a tongue, said pin being preferably formed with a combination-tool.

The doubletree is provided with four transverse openings 3, two of which are arranged near the ends of the doubletree and the other two are located within a short distance of the 40 central opening, and the transverse openings 3 are adapted for the reception of arms or rods 4, that are preferably formed integral with a back piece 5, said arms being provided at their ends, which are arranged in front of the 45 doubletree, with trace-hooks. The arms or rods 4 and the connecting back piece 5 perform the functions of an ordinary singletree, and in order to prevent jar to the animal when starting a heavy load or during the passage of a vehicle over rough surfaces the 50 back bars 5 are cushioned by springs 6, that

are constructed of flat metal and are slightly curved and are provided at their ends with recesses 7, to receive the back rods 5 where they bend and merge into the arms 4, and 55 when the rods or arms 4 are pulled upon the tendency is to compress the flat curved springs 6, which form a cushion.

The doubletree is provided on its lower face with clip-plates 8, that are arranged upon 60 each side of the central opening 2 and are L-shaped and are provided with longitudinal slots 9, through which pass screws or the like, by means of which the clip-plates are secured to the whiffletree and are adapted to be adjusted against the tongue to limit or prevent any swinging motion of the doubletree and perform the function of stay-chains and dispense with the latter.

The depending portions of the doubletree, 70 which are adapted to be arranged along the side faces of the tongue, are provided with slots 10, by means of which the clip-plates can be secured to the tongue.

The whiffletree 1 is provided with longitudinal grooves or slots 11, which terminate at the ends of the tree and are adapted to receive rods or bars 12, that are provided at their ends with trace-hooks, by means of which an additional horse or horses can be attached 80 to the vehicle, when desired. The rods or bars 12 are provided at their inner ends with spiral springs 13, that are arranged to be compressed when the rods or bars 12 are concealed within the doubletree, and are adapted 85 to force the bars therefrom, when desired, the bars or rods being retained within the groove by suitable locking means, such as pins or the like.

What I claim is—

1. The combination of a doubletree provided with transverse openings, the rods or arms 4, arranged in said openings, and the back rods 5, connecting the arms or rods, and the springs interposed between the doubletree and the back rods and forming cushions, substantially as and for the purpose described.

2. The combination of the doubletree provided with transverse openings, the rods or arms provided at their ends with trace-hooks 100 and arranged in said openings, the back rods formed integral with said rods or arms, and

the curved flat springs interposed between the doubletree and the back rods and forming cushions, substantially as described.

3. The combination of the whiffletree provided with the transverse openings and the longitudinal grooves or slots 11, the rods or arms 4, arranged in the transverse openings, the back rods, the springs interposed between the back rods and the whiffletree, the spring-actuated rods or bars concealed in the grooves or slots 11, and the adjustable L-shaped clip-plates provided with the slots 9 and 10, substantially as described.

4. A whiffletree provided with longitudinal grooves terminating at its ends, and having spring-actuated rods or bars concealed in said grooves and provided with trace-hooks, substantially as and for the purpose described.

In testimony that I claim the foregoing as my own I have hereto affixed my signature in presence of two witnesses.

CHARLES W. EDWARDS.
